FASTENING PULLING MACHINES

Lawrence E. Steimen, Topsfield, Mass., assignor to United Shoe Machinery Corporation, Flemington, N. J., a corporation of New Jersey

Application August 26, 1953, Serial No. 376,618

3 Claims. (Cl. 12—16)

This invention relates to fastening pulling machines, and is herein illustrated as embodied in a machine for pulling insole tacks from shoes.

In fastening pulling machines of the type referred to, as heretofore constructed, difficulties have been experienced in connection with readily and quickly locating fastenings in a shoe relatively to the pulling tool, in pulling deeply embedded fastenings, and in disposing of pulled fastenings in such manner as to prevent likelihood of injury to the operator.

In view of this it is an object of the invention to provide an improved fastening pulling machine especially adapted to facilitate presentation of the work to a pulling tool, together with novel mechanism for actuating the tool and for controlling the relative positions of the tool and the work during the pulling operation.

To this end, and as shown, the invention provides a rotary disk in which is mounted, for radial movement, a tool holder carrying a fastening pulling tool, there being a cam engaging the holder for controlling the path of movement of the tool, and a work-guide positioned adjacent to the path and movable into predetermined positions relatively to the path for locating the work at the operating point. Preferably and as illustrated, the disk is driven from a shaft by a one-revolution clutch, the disk being normally held stationary until the clutch is tripped by electrical means, operation of which is initiated by movement of the guide in presenting the work to the machine. As shown, there is also provided work illuminating means including a lamp, light from which passes through an opening in the disk when the latter is stationary, to light an area of the work and thereby indicate the position of the operating point to which a fastening is to be presented.

These and other features of the invention are disclosed in the following specification and in the accompanying drawings, and are pointed out in the claims.

In the drawings,

Fig. 1 is a view in side elevation of a tack pulling machine embodying one form of my invention;

Fig. 2 is a plan view of the machine;

Fig. 3 is a cross sectional view taken along line III—III of Fig. 2; and

Fig. 4 is a wiring diagram of the machine.

The illustrated machine comprises a standard 10, Fig. 1, carrying a head 12. Mounted in the head is a tack pulling tool 14 arranged for movement in a generally circular path but also movable radially along a portion of the path to engage and pull a tack such as tack 16 in a shoe 19 located in operative position relatively to the path of the tool by means of a support 20 and a guide 22.

The tool 14 is in the form of a pick having a grooved end 24, Fig. 3, for engaging tacks to be pulled and a shank 26. The shank is held in a bore 28 in a tool holder 30 by a set screw 32.

The holder 30 is in the form of a slide mounted in a radial slot 34 in a circular disk 36 mounted upon a shaft

2

38 arranged to be rotated by a motor driven pulley 39. Surrounding the disk is a housing 40 within which is located a stationary cam 42 held in position by bolts 44. The cam is generally circular in shape but has a flat portion 46 and an adjacent sharply reentrant portion 48 followed by a rise 50. The cam is in position to be engaged by a roll 52 on the tool holder which is normally forced outwardly of the center of the disk by a spring 54. This construction is such that upon rotation of the disk 36

10 the end of the tool moves through a circular path determined by the engagement of the roll with the cam, until the operating point is approached whereupon the spring forces the tool holder and tool outwardly with the roll against the flat portion 46 of the cam, then rapidly outward with the roll in the reentrant portion 48, after which the tool holder and tool are retracted when the roll rides up upon the rise 50.

The end portion of the tool is inclined slightly relatively to the shank 48 in the direction of movement of the disk to facilitate engagement of the tool with the tack beneath its head.

The path of the pulling tool forwardly of the operating point is enclosed by a semicircular safety guard 58 having a U-shaped cross section, the guard being secured 25 to the cam plate by screws 60. The guard 58 also functions to direct pulled tacks away from the operating point to the top of the machine where they can be received in a receptacle, not shown.

Near the operating point the guard is flared outwardly 30 to form the support 20 against which a shoe from which tacks are to be removed can be located. Location of the shoe relatively to the tool path is further facilitated by the guide 22. The guide is a U-shaped member having vertical side walls 62 and a connecting bottom part 64 35 which is normally positioned in advance of the support 20 below the path of the tool and spaced from the support by a distance several times as great as the width of a tack head.

The guide forms a depending part of one end of a 40 lever 66, Fig. 1, pivoted at 68 on the head 12. The lever and guide are normally forced outwardly of the path of the tool by means of a spring 70 positioned between the upper face of the lever and an abutment 72 in the casing. Outward movement of the guide is limited by a set screw 45 74, on an arm 76 on the lever, and arranged to engage a boss 78 on the head.

Inward movement of the guide is limited by a stop lever 80 having arcuate faces 82 and 84, at different levels heightwise of the lever, arranged to act as stops to engage 50 a setcrew 86 on the lever 66.

Either of the faces may be positioned in operative relation to the set screw. To this end the lever 80 is mounted on a pivot 88 about which the lever can be moved by a link 90 connected to a foot treadle 92. The treadle is 55 normally held in its upper position by a spring 94 extending between a collar 96 on the link and an abutment 98 on the head. In this position the lever 80 is located with the face 82 in operative relation to the set screw 86. Upon depression of the treadle the face 84 60 is brought into operative relation to the setscrew.

With the construction and arrangement of parts thus far described it will be apparent that a lasted shoe such as shoe 19 can be readily presented in operative relation to the tool path by resting the insole 21 thereof against the support 20 with a tack in the insole located between the support and the movable guide 22. By forcing the shoe upwardly against the guide utilizing the support as a pivot the tack head is brought into the path of the tool and upon rotation of the tool is pulled. The movement of the shoe into the path of the tool is arrested by the face 65 82 of the stop lever. However, if a tack is deeply embedded in the insole of the shoe, depression of the treadle 70

will result in placing face 84 in operative position with the result that the shoe in engagement with the guide 22 can be moved further inwardly to permit the tool to dig into the insole behind the tack head sufficiently deeply to engage and pull the tack.

The shaft 38 is rotated by means of a one-revolution clutch 100, of well-known construction, having a clutch bolt 102 for effecting engagement of the pulley 39 and shaft 38 upon release of a clutch rod 104. The rod is normally forced to the left, Fig. 2, into clutch disengaging position by a spring 106 and is moved to the right by the plunger 108 of a solenoid 110 which is actuated at the proper time by operation of the lever 66 when the work is pressed upwardly against the guide 22.

The outer end of the lever 66 carries a set screw 112 movable with the lever to actuate a push button switch 114, Fig. 1, in an electric circuit for energizing the solenoid 110 in initiating a tack pulling operation.

As shown in the wiring diagram of Fig. 4 the solenoid 110 is connected by a lead 116 to one side 118 of a power line which extends to a contact 120 of the switch 114. A lead 122 extends from the other contact 124 to contacts 126 and 128 of a relay 130. The relay has a lower armature 131 normally bridging the contact 128 and a contact 132 connected to a lead 134 extending to a coil 136 of a relay 138. The coil is connected by lead 140 to the other side 142 of the power line. A motor 141 for driving the pulley 39 is connected across the power lines 118 and 142, and is controlled by a line switch 143.

The relay 138 has a contact 144 connected by a lead 146 to lead 140 and a contact 148 connected by a lead 150 to the solenoid 110. The circuit across contacts 144 and 148 is normally open but is arranged to be closed by armature 152 when the coil 136 is energized, thus to effect operation of the solenoid 110 to initiate a single revolution of the shaft 38.

The coil 136 is connected by a lead 154 to one end of a coil 156 of the relay 130 the other end of the coil being connected to a contact 158 which can be connected to the contact 126 by operation of the upper armature 160 of the relay 130. The coil 156 is also connected by a lead 162 to one side 164 of a switch 166, Figs. 1, 3 and 4, the other side 168 of which is connected by a lead 170 to the power line 118. The circuit through the switch 166 is normally open but is arranged to be closed by operation of a cam 168 on the shaft 38, shortly after rotation of the shaft has commenced.

Thus, when the work is pressed against the guide 22, the switch 114 is closed and the circuit through lead 122, armature 131, lead 134 and coil 136 is energized causing flow of current through lead 150 and the solenoid 110 which causes the plunger 108 to trip the clutch 100 effecting one revolution of the shaft 38 and an operation of the pulling tool 14.

As the shaft 38 rotates the cam 168 closes the switch 166 with the result that current passes through coil 156 closing the circuit across contacts 126 and 158, and opening the circuit through coil 136. This results in opening the circuit through the solenoid 110, and the spring 106 forces the plunger 104 into clutch disengaging position, and the shaft and tool are subsequently brought to rest after a single revolution.

As the shaft nears the end of a single revolution the cam 168 releases the switch 166. If, after the switch 166 has been released, the work is still held against the work guide 22 current through the coil 156 will maintain the armature 131 in its inoperative position with the circuit through the coil 136 open with the result that a second operation of the clutch is prevented. However, when the work is moved away from the work guide 22 the switch 114 is released thus opening the circuit through

the coil 156 permitting the armatures 131 and 160 to assume their original positions.

As shown in Fig. 3, the operating point of the machine lies along the path of the tool during its radial movement under control of the spring 54 and the cam 42, and located slightly in advance of the nose portion 20 of the guard. In presenting a shoe to the machine the tacks therein should be successively located with their heads extending into the path of the tool at that point. This is facilitated by spot illumination of the insole of a shoe presented to the guide 22 in such manner that the spot indicates the position into which a tack should be moved properly to locate it along the path of the tool. To this end, the head 12, Fig. 1, carries an electric lamp 170, light from which is directed through an opening 172 in the head and an opening 174 in the disk 36 at such times as the disk is stationary. The openings are in alignment with the operating point and serve to direct a spot of light upon the insole of a shoe initially presented to the guide 22.

In the operation of the machine a shoe is presented bottom up to the guard 20 and guide 22 and is moved along the latter until a tack to be pulled is located within the spot of light appearing upon the insole. Pressure then applied upwardly against the guide actuates the switch 114 resulting in a single revolution of the tool to effect pulling of the tack.

Having thus described my invention what I claim as new and desire to secure by Letters Patent of the United States is:

1. A fastening pulling machine comprising a rotary disk, a tool holder slidably mounted radially of the disk, a fastening pulling tool mounted on the holder, resilient means normally forcing the tool outwardly of the axis of the disk, a circular cam engaging the holder to limit outward movement of the tool thus to control the path of movement of the tool, a work guide adjacent to the tool path comprising a pivoted lever, and stops for limiting movement of the lever in a direction toward the path.

2. A fastening pulling machine comprising a rotary disk, a tool holder slidably mounted radially of the disk, a fastening pulling tool mounted on the holder, resilient means normally forcing the tool outwardly of the axis of the disk, a circular cam engaging the holder to limit outward movement of the tool thus to control the path of movement of the tool, a work guide adjacent to the tool path comprising a pivoted lever, stops for limiting movement of the lever in a direction toward the path, and means responsive to movement of the lever for initiating rotation of the disk.

3. A fastening pulling machine comprising a rotary disk, a tool holder slidably mounted radially of the disk, a fastening pulling tool mounted on the holder, resilient means normally forcing the tool outwardly of the axis of the disk, a circular cam engaging the holder to limit outward movement of the tool thus to control the path of movement of the tool, means normally operative for retaining the disk in stationary position with the tool about 180° away from the operating point, an opening in the disk, and a lamp for illuminating the operating point when the disk is stationary.
